Primary Examiner — Rachel A. Voorhies*Assistant Examiner* — Benjamin D. Wannemacher(74) *Attorney, Agent, or Firm* — McHale & Slavin, P.A.(57) **CLAIM**

The ornamental design for a rake head, as shown and described.

DESCRIPTION

FIG. 1 is a bottom front right perspective view of the rake head of the present invention;

FIG. 2 is front view thereof;

FIG. 3 is a rear view thereof;

FIG. 4 is a right side view thereof;

FIG. 5 is a left side view thereof;

FIG. 6 is a bottom view thereof;

FIG. 7 is a partial enlarged view taken along lines 7-7 of FIG. 3; and,

FIG. 8 is a top front right perspective environmental view thereof.

The portions of the figures illustrated in dash-dot broken lines form no part of the claimed design.

The portions of the figures illustrated in dash-dot lines illustrate limits to the enlarged partial views and form no part of the claimed design.

1 Claim, 7 Drawing Sheets(56)
